UNITED STATES PATENT OFFICE.

EDWARD CRAIG, OF ST. JOSEPH, MICHIGAN, ASSIGNOR TO SARANAC MACHINE COMPANY, OF BENTON HARBOR, MICHIGAN, A CORPORATION OF MICHIGAN.

INSIDE BOX-END-STAPLING MACHINE.

1,254,395.

Specification of Letters Patent. Patented Jan. 22, 1918.

Application filed March 22, 1915. Serial No. 16,230.

To all whom it may concern:

Be it known that I, EDWARD CRAIG, a citizen of the United States of America, and resident of St. Joseph, Berrien county,

Michigan, Niles Avenue, have invented a certain new and useful Improvement in Inside Box-End-Stapling Machines, of which the following is a specification.

My invention relates to stapling machines of the kind employed for stapling the heads or end walls of wire-bound boxes in position at the ends of the box.

Generally stated, the object of my invention is to provide an improved construction and arrangement whereby, in a so-called inside end stapler of this general character, the staple is made and driven at a point inside of the box, and in one and the same plane, thereby obviating the necessity of forming the staple in one plane and then transferring it to another plane for insertion, and whereby the staple is formed at a point very close to the point of insertion thereof in the box-head or end wall.

Another object is to provide an inside end stapling machine of this kind, as above stated, having means other than the staple-former for cutting off the wire, by a short movement thereof as compared with the relatively long stroke of the staple-former, and whereby the length of the section wire thus cut off or severed is greater than the width of the staple-former, thereby insuring a staple of the desired length and size, notwithstanding the fact that the staple-former is of a width and shape to facilitate the driving of the staples quite close to the inner surface of the side walls of the box.

It is also an object to provide certain details and novel features of construction and combinations tending to increase the general efficiency and desirability of an inside end stapler of this particular character.

To the foregoing and other useful ends my invention consists in matters hereinafter set forth and claimed.

In the accompanying drawings Figure 1 is a side elevation of an inside end stapler embodying the principles of my invention.

Fig. 2 is an enlarged plan of the said machine, showing the outer end portion thereof broken away for convenience of illustration.

Fig. 3 is a vertical section, on a larger scale on line 3—3 of Fig. 2.

Fig. 4 is an enlarged side elevation, partly in vertical section, of a stapling mechanism and adjacent parts shown at the left in Fig. 1.

Fig. 5 is a detail section on line 5—5 in Fig. 4.

Fig. 6 is a large section on line 6—6 in Fig. 4.

Fig. 7 is a similar section on line 7—7 in Fig. 4.

Fig. 8 is a similar section on line 8—8 in Fig. 4.

Fig. 9 is an enlarged side elevation of the stapling mechanism, showing the side plate of the housing or casing thereof removed to bring the parts into view.

Fig. 10 is a perspective of the upper end portion of the staple-former.

Fig. 11 is a similar view of the staple-anvil.

Fig. 12 is a perspective of the stapling parts and mechanism shown in Fig. 9, illustrating the manner in which the end portion of the wire is fed directly across the path of the bifurcated staple-former, and also directly across the path of the staple-driver which slides in the slot of the said staple-former.

Fig. 13 is a perspective of the separate or independent wire-cutter which is employed in conjunction with the staple-forming and driving devices, whereby the cutting of the wire is not dependent upon the staple-former, and whereby the length of the staple is not dependent, as is ordinarily the case in mechanism of this kind, upon the width of the staple-former.

Fig. 14 is a perspective of the upper end portion of the staple-driver.

Fig. 15 is a detail plan view of the support or arm upon which the box rests while being stapled, and which engages the inner surface of the side walls of the box to cor-

rectly position the latter during the successive stapling operations required for securing the box-head or end wall in place.

As thus illustrated, and referring to Fig. 5 1, my invention comprises a base A provided with an upright post or pillar *a* for supporting the various operative parts in suitably elevated positions. The arm or support B is rigidly secured to the upper end 10 of the post or pillar *a* and is of the shape shown in Fig. 15, when viewed from above, being adapted to support the box-head or end wall flatwise upon its top or upper surface, and to engage the inner surface of the 15 side walls of the box.

The stapling mechanism which is disposed at the outer end of the arm or support B is shown in Figs. 4 and 9 to 14 inclusive, and also in Figs. 5 to 8 inclusive, and comprises 20 a staple-former C consisting of a flat metal bar provided at its upper end with a slot *c* having grooves *c*¹ for the staple, and at its upper end the said staple-former is provided with notches *c*² which receive the wire 25 when the latter is fed into position. At its lower end the said staple-former is provided with a notch *c*³ to receive the end portion of the latch *c*⁴, which latter is pivoted at *c*⁵ on the staple-driver D, the latter being in 30 the form of a flat bar resting flatwise against the side of the staple-former. As shown in Fig. 12, and also in Fig. 4, the end of the latch *c*⁴ is in engagement with the lower end of the staple-former, whereby the latter and 35 the staple-driver will move upward together; but when the shoulder *c*⁶ of said latch strikes the stationary cam *c*⁷, the latch is then tripped to permit upward movement of the staple driver while the staple-former re- 40 mains stationary with its bevel *c*⁸ against the under side of the box-head or end wall. This cam *c*⁷ is formed on a bar or strip *c*⁹ which is held in the housing or casing *c*¹⁰ by means of a screw *c*¹¹, or in any suitable manner, the said cam being the end of a groove 45 or similar formation *c*¹² formed for a suitable distance along the said bar or strip. The staple-driver D has a portion *d* which slides in the slot *c* of the staple-former, and 50 which is provided with ribs *d*¹ that slide in the grooves *c*¹ of said slot, whereby the staple-former serves as a guide for the upper end portion of the staple-driver. As shown, the said staple-former is provided with a 55 downwardly extending rod *c*¹³ which extends through a lug *c*¹⁴ on the lower end of the staple-driver and a spring *C*¹⁵ is interposed between said lug and the lower end of the staple-former, on said rod to hold the 60 staple-former against the work after said former is unlocked from the driver, and whereby the staple-former and staple-driver are restored to their normal relative positions after the driving of the staple. It will

also be seen that the staple-driver D is provided on one edge thereof with teeth *d*² which form a rack for engaging the toothed segment E, the latter being supported by horizontal bolt or stud *e* secured to the side wall *b* of the support B, inside of the latter, 70 whereby the staple-former and staple-driver are reciprocated up and down by the oscillation of the said toothed segment or fragmentary pinion. As shown in Fig. 5, the loop bar F, or staple-anvil, is secured to a 75 flat spring *f*, this spring resting flatwise against the staple-driver and being secured to the casing *f*¹ of the staple mechanism by screws *f*² at the lower end thereof. This anvil F is provided with a slot or notch *f*³ to receive the wire, and also with a cam *f*⁴ immediately below said notch or wire slot. Thus, and when the upper end of the staple-driver portion *d* engages the cam *f*⁴, during the upward movement of the staple-driver 85 and staple-former, the spring *f* is flexed away from the adjacent flat surface of the staple-driver, leaving the staple in the grooves *c*¹ of the staple-former. It will be seen that the anvil F normally occupies the 90 slot *c*, and is in position to coöperate with the upper end of the staple-former in bending the length of wire into the desired form, as the prongs of the staple-former move upward at opposite sides of said anvil. 95

The mechanism for cutting the wire comprises a reciprocating wire cutter G arranged to slide up and down on the upper and inner edge of the staple-former, being provided with a knife *g* at its upper end, 100 which knife is disposed obliquely and in position to leave the wire with a tapered or beveled sharp end, and with a notch *g*¹ for engaging the end portion of the bell crank lever H which is pivoted at *h* on the side 105 wall *b* of the support B, whereby said lever is operative to reciprocate the cutter G up and down. For this purpose the lever H is provided at its upper end with a roller *h*¹ for engaging the cam *h*² on the hub portion 110 of the toothed segment E, whereby the cutter G is given only a slight movement as compared with the relatively long stroke of the staple-former. A stationary guiding member *g*² is secured in position to coöperate with the knife *g*, and the wire is fed through this guiding member by a feed tube *g*³ suitably held in position at right angles to the length of the staple-former at a point 115 opposite the notch *f*³ of the anvil. A rod *e*¹ is pivotally connected with an arm *e*² extending upwardly from the hub of the toothed segment E, and when this rod is moved in the direction indicated by the arrow in Fig. 9, the different elements of the 120 stapling mechanism are operated upwardly, in the manner described, to insert the staple I through the box-head or end wall *i* and 125

into the cleat i^1 of the box. It will be seen that at this time the side walls i^2 of the box engage the front surface b^1 of the arm or support B, whereby the staple is driven or inserted at a point located a suitable distance from the said side wall. When the rod e^1 moves in the reverse direction, the elements of the stapling mechanism are then brought back to normal position, the toothed segment E having a roller e^2 which engages the lever H to insure complete downward movement of the wire-cutter. It will be observed, at this juncture, that the staple-driver and staple-former and the housing thereof are disposed at such an angle that the direction of insertion of the staple is on a line extending through the plane of the side wall of the box, whereby the staple is inserted obliquely in the manner shown in Fig. 9. It will also be seen that with this construction and mode of operation the staple is driven in the same plane in which it was made, thus obviating the necessity of means for shifting it from one plane to another, or from one position to another, before thrusting it forward for the purpose of insertion.

With the construction shown, it will be seen that one leg of the bifurcated staple-former C (the leg nearest the side wall i^2 of the box) is a little longer than the other leg or prong of the staple-former, so that it finally bears against the under side of the box-head i , during the driving of the staple. Also, the wire is fed and cut off in such manner that, when formed into a staple, the leg of the staple nearest the box-side i^2 is longer than the other leg, whereby the two points of the staple, although of unequal length, enter the box-head and the cleat at about the same time, or substantially so, notwithstanding the oblique direction in which the staple is inserted (see Fig. 9). In this way, the two points of the staple are inserted about the same distance in the cleat, and the two points enter the work practically at the same time, so that the pressure is the same at both sides of the staple, but which would not be the case if one point entered first, as in that event the pressure would be all on one side of the staple until the other point entered the work.

The means or devices for feeding the wire comprise a pair of feed rolls J and K, these rolls being geared together for the purpose of feeding the wire into the tube j which leads to the short feed tube g^2 from which the wire is fed to the stapling mechanism. A ratchet wheel k is secured to the roll K and arranged in position to be engaged by the pawl k^1 which rests on the bracket or support z^2 , and which is provided at its other end with a fork-shaped portion k^2 that rests on the shaft L at the other end of

the machine. Said shaft is provided with a cam k^4 for engaging a roller k^5 on the pawl k^1 , whereby the latter is reciprocated back and forth for the purpose of operating the ratchet wheel k , it being understood that the said cam is of such character that the wire will be fed at the proper time—that is to say, some time previous to the upward movement of the staple-former. A spring k^6 serves to retract the said pawl k^1 of the wire feeding mechanism.

The rod e^1 is provided at its end with a portion e^4 having a slot e^5 for the shaft L, and having also a roller e^6 for engaging the cam groove e^7 of the cam M, which latter is secured to the shaft L in any suitable manner. In this way, it will be seen that the rotation of the shaft L, which latter is supported in suitable bearings l on the body frame of the machine, serves to operate both the stapling mechanism and the wire feeding devices, the two cams being timed to operate in the proper manner.

A lever N is pivoted on the body frame at n and provided at its outer end with an adjustable screw n^1 for engaging the top of the cleat i^1 of the box. See Figs. 1, 4, and 9. The other end of this lever N is provided with a roller n^2 for engaging the periphery or outer edge of the cam M, it being observed that the said periphery or edge is of a shape to cause the roller n^2 to move up and down when shaft L is rotated. In this way the screw n^1 is caused to move down against the cleat of the box at the proper time to resist the upward thrust of the staple-driver. Then when the staple is driven the pressure relaxes, inasmuch as the cam M permits the roller n^2 to move downward, whereby the box is unclamped to permit shifting thereof to a new position for receiving the next staple.

A clutch O on the shaft L is controlled by a foot lever o through the medium of a clutch-connecting rod o^1 , said lever being suitably pivoted on the base of the machine, whereby the operator or attendant may control the operation of the machine at will.

Thus it will be seen that the staple is formed at a point quite close to the point of insertion in the box, notwithstanding the fact that it is made and driven inside of the box, and notwithstanding the further fact that the staple is driven quite close to the side wall of the box. In other words, the staple is never shifted laterally from the time it is formed until the time it enters the box. It is driven in a straight line directly from the forming position into the box.

With further respect to the means for cutting the wire, it will be seen that the severing point is a distance from the staple-former, and it will also be seen that the wire is fed past the end of the staple-

4

former, whereby the opposite ends of the severed section of wire project at the opposite sides of the staple-former. Consequently, and with this method, a much longer and larger staple is formed than would be the case if the staple-former itself were employed for cutting off the wire. In order to properly drive the staple close to the side wall of the box, the staple-former is reduced in width, and the use of the staple-former for cutting the wire is further precluded or rendered undesirable by the beveling of the upper end of the staple-former to enable it to bear against the under side of the box-head or end wall during the insertion of the staple. For this reason, therefore, a separate and distinct wire cutter is employed, such as the cutter G, as previously described, and the feeding of the wire is so gaged or adjusted that the severed section of wire is longer than the width of the staple-former, thus insuring the proper length for the staple, notwithstanding the size and formation of the staple-former.

With further respect to the cutting of the wire, it will be seen that the end of the tube g^3 can be beveled on one side, in a suitable manner, and thereby adapted to cooperate with the knife g to cut off the wire when the cutter G moves upward. It will be understood, however, that any suitable means can be employed for coöperating with the cutter G to sever the wire.

35. What I claim as my invention is:—

1. A machine for inserting staples outwardly through the heads and into the cleats of wirebound boxes, by successive operations inside of the box, comprising means for engaging the inner surfaces of the box to properly position the same for the insertion of the staples, and a staple forming and driving mechanism associated with said means, arranged to operate inside of the box, said mechanism including devices arranged to form the staple in the plane of insertion thereof, and said mechanism having a driver arranged to operate in said plane to carry the staple in a straight line directly from the forming position to the place of insertion.

2. The said machine, as set forth in claim 1, one of said devices being a bifurcated staple former having its end shaped to engage the inner surface of the box to serve as a guide for the staple, and said driver sliding in said staple former.

3. The said machine, as set forth in claim 1, the insertion being in a direction oblique to and through the plane of the adjacent side of the box.

4. The said machine, as set forth in claim 1, one of said devices being a bifurcated staple former, and said mechanism having

instrumentalities for feeding and cutting off 65 a section of wire longer than the width of said staple former.

5. The said machine, as set forth in claim 1, said devices including a staple former, and a wire cutter separate from said devices 70 and movable only a short distance as compared with the relatively long stroke of the staple-former.

6. The said machine, as set forth in claim 1, said devices including a movable anvil, a 75 staple former coöperating with said anvil to form the staple, and a staple driver, said anvil having means to engage said driver, and a spring to permit movement of said anvil by said engagement thereof with the 80 staple driver.

7. The said machine, as set forth in claim 1, said devices including a staple former and a staple driver disposed flatwise together, a flat spring secured at one end and arranged flatwise against the staple driver, an anvil on said spring to coöperate with the staple former in bending the wire, a cam on said anvil, and means on the staple driver to engage said cam and push the anvil from the operating position thereof. 88

8. The said machine, as set forth in claim 1, a shaft remote from said mechanism, a wire-feeding means adjacent said mechanism, a clamp for holding the box down, and cams on said shaft to operate said mechanism and wire-feeding means and clamp. 95

9. A machine for inserting staples, comprising a staple-former, a staple-driver, a wire-cutter disposed at one side of said staple-former, a device to feed the wire across the path of said staple-former and staple-driver and wire-cutter, a member connected to actuate said staple-driver, a locking device to connect said staple-driver with said staple-former, means for automatically causing said locking device to unlock the staple-former from the staple-driver after the formation of the staple, an element for actuating said wire-cutter, and means on said member to operate said element, the arrangement being such that said staple-former has a longer stroke than said wire-cutter. 100

10. The said machine, as set forth in claim 9, in which said member comprises an oscillating toothed segment, the staple-driver having rack-teeth to engage said segment, and said element comprising a pivoted lever having one end thereof arranged in operative relation to the means on said member. 115

11. The said machine, as set forth in claim 9, in which said member is provided with means to engage said element to retract the wire-cutter. 120

12. The said machine, as set forth in claim 9, in which said feeding device is operable to feed the wire a distance greater than the 125

width of the staple-former, so that the severed length of wire extends at both ends beyond the staple-former.

13. The said machine, as set forth in claim 1, in which said devices are adapted to form the leg of the staple adjacent the side of the box longer than the other leg thereof, and in which the direction of insertion is oblique to the side of the box, so that the two

points of the staple although of unequal length enter the head and cleat substantially at the same time.

Signed by me at Chicago, Illinois, this 17th day of March, 1915.

EDWARD CRAIG.
